VISE

Nathan W. Warman, Los Angeles, Calif.

Application November 2, 1935, Serial No. 47,981

4 Claims. (Cl. 81—33)

This invention contemplates a vise of the so-called "quick action" type which is of simple form and construction and may be economically manufactured.

As is well known to those familiar with the art, the conventional type of vise comprises a movable jaw and a fixed jaw, the movable jaw being adapted for movement toward and away from the fixed jaw through the medium of a screw which is engaged either in the body which carries the fixed jaw or in a nut suitably secured to such body. In these conventional types of vises both the opening and closing of the jaws must be effected entirely by rotating the screw so that considerable time is lost in opening and closing the jaws, especially where the work varies considerably in thickness between the engaged surfaces.

The quick action vise, contemplated by this invention, embodies a fixed jaw and a movable jaw and a screw for tightening or clamping the jaws, but in addition to these elements, the vise embodies means whereby the movable jaw can be moved away from and toward the fixed jaw by merely pushing or pulling the same. In other words, my vise may be operated by first pulling the movable jaw to open the jaws, then pushing the movable jaw into engagement with the work after which the work is clamped by a few rotations of the screw. To release the work the screw is rotated a few times in the reverse direction, after which the movable jaw can be pulled away from the fixed jaw.

It is a primary object of this invention to produce a vise, of the class described, which is of rugged construction and is fool-proof in its operation. It is an important feature of my improved vise that it embodies no split nuts or cams which are subject to excessive wear, are liable to get out of adjustment and are adapted for use in connection with light work only. The vise contemplated by this invention is especially adapted for use in connection with heavy work, although it may be used with work of any nature.

It is a further object of this invention to produce a vise of the class described which is provided with a novel type of swivel base whereby it may be easily and quickly set at various angles within a radius of 360°.

The details in the construction of a preferred form of vise contemplated by this invention, together with other objects attending its production, will be best understood from the following description of the accompanying drawing, which

is chosen for illustrative purposes only, and in which—

Fig. 1 is an elevation, with parts in section, showing a preferred form of vise contemplated by my invention;

Fig. 2 is an enlarged fragmentary view, with parts broken away, showing further details in the construction and operation of the vise;

Fig. 3 is a section taken on the line 3—3 of Fig. 2;

Fig. 4 is a sectional elevation taken on the line 4—4 of Fig. 1;

Fig. 5 is a plan section taken in a plane represented by the line 5—5 of Fig. 4;

Fig. 6 is a fragmentary plan view taken in the direction of the arrow 6 of Fig. 5; and

Fig. 7 is a perspective view showing a preferred form of clamping wedge designed for use in conjunction with the swivel base contemplated by this invention.

More particularly describing the invention, as herein illustrated, reference numeral 11 indicates what I may term as a fixed jaw supporting housing, or a fixed body member, which is shown as being mounted on a swivel base generally indicated by reference numeral 12.

The body member 11 has a jaw 13 formed, or otherwise secured, to what I may term its front end, and is provided with a longitudinal passage 14 which receives a traveling member or a movable member 15 which will be hereinafter referred to as an adjustable jaw supporting housing. The movable member 15 is provided with a jaw 13' on its front or outer end which is opposite the fixed jaw 13. The portion of the movable member, received in the passage 14, and such passage are formed of non-circular cross section, so that the movable member will not rotate or wobble relative to the fixed member. In the form shown, the inner or rear extending portion of the movable member is rectangular in cross section and the passage 14 is provided with flat facets 17 and 17' which form bearings for the member 15.

The member 15 is provided with a longitudinal passage 18 which receives a screw shaft 19. The shaft is held against longitudinal movement in the passage by a collar 20 secured to the shaft by a key 20' contained in a notch or recess 21 in the bottom of the movable member. The inner end of the movable member is provided with an enlarged chamber 22 which contains a nut or block 23 having internal engagement with threads 24 on the end of the screw shaft. It is important that the nut or block 23 be slidable and non-rotatable relative to the chamber, and,

for this purpose, I propose to form the chamber and the nut as shown in section in Fig. 3, although other shapes or constructions may be employed for this purpose.

It will be seen from the construction so far described that rotation of the shaft will effect longitudinal movement of the nut within the chamber, and the movable member is free to move longitudinally within the fixed member by merely pushing or pulling the movable member. It is important in attaining the object contemplated by this invention to provide means for optionally locking the nut against movement relative to the fixed member, such means at the same time being operative to release the nut so that it moves with the movable member and the screw shaft whereby the screw may be employed to clamp the jaws or release the movable member so that the jaws can be pulled apart. This is accomplished by means of a dog and ratchet mechanism which will now be described.

Reference numeral 26 indicates a recess formed in the bottom of the nut or block 23 which contains a dog 27 between its downwardly projecting end shoulders 28 and 28'. In the form shown, the dog 27 is loosely mounted in the recess and is normally supported on the bottom portion 29 of the enlarged chamber, which has an inclined surface 29' over which the dog rides. The front edge of the inclined surface 29' defines the rear edge of an opening 30, in the bottom of the chamber, through which the dog is adapted to drop into engagement with teeth 31 in the bottom of the passage 14. The teeth 31 may be cast or otherwise formed directly in the material of the fixed body, but, for the purpose of increasing the strength of the unit and facilitating its repair, I prefer to form the teeth on a separate hardened plate 32 which is secured in a recess formed in the bottom of the passage 14 by means of screws 33 and 33'.

In operation, the screw shaft 18 is first rotated in one direction by means of the bar 35 in the head 36 to retard the nut to the position shown in Fig. 1 where the dog is shown supported on the bottom of the enlarged passage. The movable member 15 may then be pulled out to any predetermined point to admit the reception of work between the jaw, after which it is pushed back until the jaw 13' engages the work. The screw is then rotated in the opposite direction during which the nut is advanced to the position shown in Fig. 2 where the front of the dog 27 drops into engagement with one of the teeth 31. Further rotation of the shaft is effective to move the jaw into clamping engagement with the work.

In order that the movable member may not be inadvertently pulled entirely out of the fixed member, I provide the bottom of the movable member with a groove 38 which receives the top or inner end of the screw 33' or other suitable removable stop member. Reference numeral 39 indicates a shelf provided on the front of the fixed member to support the front portion of the movable member. Reference numeral 41 indicates a cross pin mounted across the rear of the passage through the fixed member where it is received in a notch 42 in the inner member when the vise is closed. This pin prevents the nut being inadvertently screwed off the screw shaft in the event it is provided with a thin or narrow dog.

It was pointed out above that one object of this invention was to provide a novel type of swivel base which is especially adapted for use

in connection with a vise of the type contemplated by this invention. This base, generally indicated by numeral 12, comprises a base plate 42, the underside of which is recessed as indicated at 43 and the top of which is provided with a projection 44 which is shaped as the inverted frustum of a cone. Reference numeral 45 indicates a socket member mounted over the projection 44 with its lower annular edge 46 engaging an annular bearing face 47 on the base plate. This socket member, which is in the nature of an inverted cup, is cast with or otherwise secured to the fixed body member 11 of the vise. A screw 48 extending through an opening 49 in the top of the projection 44 into threaded engagement with the top of the inverted cup or the bottom of body 11, as the case may be, holds these two members together. The screw 48 is provided with a threaded pin 50 which extends through the screw into engagement with the 20 threaded opening in the base plate for adjusting the compression between the bearing surfaces 46 and 47.

For the purpose of locking the vise in various positions of angular adjustment upon the base plate, I provide the periphery of the upwardly flared projection 44 with a plurality of recesses or teeth 52. The teeth 52 are adapted to be engaged by correspondingly shaped teeth or serrations 53 on a wedge block 54 which is mounted in a recess 55 formed in the periphery of the socket member and has an upstanding screw pin 56 extending through an opening in the top of the socket member. The pin 56 is provided with a nut member 57 whereby the wedge block may be drawn up into locking engagement with the teeth on projection 44, and the wedge block is made of a height such that when the nut is loosened the wedge block will drop away from the teeth and permit free rotation of the socket and the vise supported thereon with respect to the base.

Various constructions may be employed in the nut member 57, but for convenience in operation, and to provide a positive lock for the nut, I propose to use a bifurcated construction as indicated at 60 within which a lever member 61 is pivoted. The free end of the lever 61 is adapted for reception between upstanding wings 62-62' on the top of the socket member, which serve to lock the screw and wedge after they have been adjusted to clamp the projection 44.

It is to be understood that while I have herein described and illustrated one preferred form of my invention, that the invention is not limited to the precise construction described above, but includes within its scope whatever changes fairly come within the spirit of the appended claims.

I claim as my invention:

1. A vise embodying: a fixed member having a longitudinal housing and a fixed jaw; rack teeth in the bottom of said housing; a movable member slidably mounted in said housing; a jaw on said movable member opposite said fixed jaw, said movable member having a passage therethrough and a chamber at the inner end of said passage; a screw shaft extending through said passage into said chamber; means on said screw shaft for restraining same against longitudinal movement relative to said movable member; a nut member non-rotatably and slidably contained in said chamber in threaded engagement with said screw, said nut having a recess in its bottom forming oppositely disposed shoulders; and a dog contained in said recess adapted to be moved in opposite directions by engagement with said

shoulders, said chamber having a bottom opening through which one end of said dog is adapted to drop into engagement with said rack when moved by said nut to aline said dog with said opening, and said chamber having an inclined bottom face adjacent said opening over which said dog is adapted to be raised out of engagement with said rack when said dog is moved in the opposite direction by said nut.

2. A vise embodying: a fixed body having a longitudinal passage therethrough; a jaw on one end of said body; rack teeth in the bottom of said passage; a travelling body slidably mounted in said passage; a jaw on the end of said travelling body opposite said first mentioned jaw; a screw shaft rotatably mounted in said travelling body means holding said screw shaft against longitudinal movement relative to said travelling body; a nut member threaded on said shaft, said nut member being non-rotatably and slidably contained within an enlarged chamber in said travelling body; projections on the bottom of said nut member forming a recess defined by oppositely disposed shoulders; and a dog loosely contained within said recess and adapted to be moved in opposite directions along the bottom of said chamber by engagement of the ends thereof with the shoulders on said nut, said chamber having a bottom opening through which one end of the said dog is adapted to drop into engagement with said rack teeth when moved by said nut to aline said dog with said opening and said dog having a downwardly projecting tooth adapted to engage the rack, the tooth on said dog having an upwardly inclined rear face adapted to ride over the edge of said opening and raise said tooth out of engagement with said rack when said dog is moved in the opposite direction by said nut.

3. A vise embodying: a fixed member having a longitudinal housing; rack teeth in the bottom of said housing; a movable member having an enlarged chamber therein slidably mounted in said housing; a nut slidably and non-rotatably mounted in said chamber; an operating shaft extending through said movable member in threaded engagement with said nut; means rotatably sup-

porting said shaft against relative longitudinal movement in said movable member; projections on the bottom of said nut forming a recess defined by oppositely disposed shoulders; a dog loosely contained in said recess, said dog being normally supported by the bottom of said chamber and adapted for movement in opposite directions by the projections on said nut, said chamber having a bottom opening through which one end of said dog is adapted to drop into engagement with said rack when moved by said nut to aline said dog with said opening, and said chamber having an inclined bottom face adjacent said opening over which said dog is adapted to be raised out of engagement with said rack when said dog is moved in the opposite direction by said nut, and cooperating jaws on said fixed and movable members.

4. A vise embodying: a fixed member having a longitudinal housing; rack teeth in the bottom of said housing; a movable member having an enlarged chamber therein slidably mounted in said housing; a nut slidably and non-rotatably mounted in said chamber; an operating shaft extending through said movable member in threaded engagement with said nut; means rotatably supporting said shaft against relative longitudinal movement in said movable member; projections on the bottom of said nut forming a recess defined by oppositely disposed shoulders; a dog loosely contained in said recess, said dog being normally supported by the bottom of said chamber and adapted for movement in opposite directions by the projections on said nut, said chamber having a bottom opening through which one end of said dog is adapted to drop into engagement with said rack when moved by said nut to aline said dog with said opening; and said dog having an upwardly inclined bottom face adapted to ride over one edge of said opening and lift said dog out of engagement with said rack when said dog is moved in the opposite direction by said nut; and cooperating jaws on said fixed and movable members.

NATHAN W. WARMAN. 45
